UNITED STATES PATENT OFFICE.

HARRY H. BATES, OF RIDLEY PARK, PENNSYLVANIA, ASSIGNOR TO WESTINGHOUSE ELECTRIC & MANUFACTURING COMPANY, A CORPORATION OF PENNSYLVANIA.

CORRELATING INDICATOR.

Application filed November 19, 1924. Serial No. 750,842.

My invention relates to indicators and especially to that type of indicators in which the results from a plurality of phenomena are so placed in juxtaposed relation that an unskilled observer is enabled to correlate these rapidly and without the use of mathematical tables or other extraneous devices.

It is well known that in modern industrial plants, many factors enter into the securing of the most efficient final result. The value of these factors is usually given by indicators of various types such as gauges, thermometers, tachometers, and the like. While these have been in the past located in juxtaposed positions for convenience in observing the same, yet they have never been so located as to permit of a graphic correlation of the results as is now rendered possible by my discovery.

An object of my invention is to produce a device in which an unskilled operator shall be able to deduce from the indications of this device a conclusion regarding the relation of the various factors which enter into the securing of an efficient result. Another purpose of my invention is to produce a device which shall bring the readings of the instruments located in various parts of the plant into a position where they can be simultaneously observed and to so arrange these readings that their inter-relations will be apparent without resorting to calculations.

A still further object of my invention is to produce a device of this type which will be light, simple, inexpensive, easy of manufacture, installation and repair, but which will at the same time be capable of use by operators without superior intellectual attainments.

These and other objects of my invention will be apparent from the following description having reference to the accompanying drawings in which I have illustrated one embodiment of my invention and in which Fig. 1 is a front elevation of the device illustrating my invention as applied to a steam boiler with accompanying stoking device. Fig. 2 is a cross-section on line II-II of Fig. 1; Fig. 3 is a detail perspective view of one of the adjustable clamps shown in Fig. 1; Fig. 4 is a diagrammatic representation of the indicator showing its relation to the boiler and stoker and Fig. 5 is a graphic representation of the variation of the factors

influencing efficient boiler operation as deduced from empirical data.

While I have shown my device as applied to a boiler and fuel feeding mechanism therefor, it should be understood that this is done solely for the sake of illustration and that my indicator is capable of wide adaptations to other apparatus in which a plurality of factors must be co-ordinated to secure the most efficient operation thereof.

Referring to the illustrations, 10 represents an indicator which consists of a board 11, mounted on any stationary surface by means of the brackets 12 which consists of a straight section 13 engaging the board 10 and secured thereto by the bolts 14-14. 70 The extremities of the straight section 13 are bent to form legs 15 which are mounted on any convenient surface by the screws 16. In the board 10 which is preferably vertical, are a number of holes 20 arranged vertically, 75 one above the other. Through each of the holes 20 extends a tube 31, preferably of glass, which is bent over at 17 and extends across the board, being held by a clamp 19 which will be described below. On the rear side of the board the tubes are connected by suitable means such, for example, as rubber tubes 21 with the instruments whose readings are to be indicated on the board. The end of the tube adjacent the clamp 19 may 80 be sealed, opened or connected to another instrument as will be pointed out hereafter. The clamp 19 consists of a strip of metal 22 having a flat portion 23 and leg portions 24 secured to the board 11. The flat portion 23 is provided with a longitudinally extended slot 26. Mounted on top of the clamp 19 and moving adjustably along the slot 26 to which it is secured by bolts 27, is a U-shaped member 29 which embraces the tube 31. 95 This construction admits of an adjustment of the inclination of the tube 31 about the hole 20 as its center. The bracket 19 may be curved about 20 as a center or it may be straight in which case the tube 31 would 100 slide relatively to the U-shaped member 29.

In applying my indicator to a boiler I have found that it is advantageous to consider five factors, namely, the evaporation in pounds per hour or, as it is sometimes expressed, the percentage of rated capacity of the boiler; fuel burned per hour, flue drop through the boiler; temperature of the

gas leaving the boiler; and the static pressure in the stoker wind box. These relations are graphically represented in Fig. 5 in which I show the most efficient values as derived from a series of experiments. The horizontal co-ordinates representing evaporation in pounds per hour and the curve A—A representing the pounds of fuel burned per hour, B—B representing the drop in pressure through the boiler in inches of water, the curve C—C representing the temperature of the gas leaving the boiler in degrees Fahrenheit, and the curve D—D representing the static pressure in the stoker wind box in inches of water.

In connecting the indicator to the boiler the tube 31 is connected at its end behind the indicator board through a vertical connection 31', the liquid in which connection forms a balance for the liquid in the tube 31, to a bypass 40 around a section of the main steam line 41. This bypass is provided with a reduced section 42 forming a Venturi meter. The connection from the end of the tube 31 terminating back of the instrument board is connected to the upstream side of the contracted portion or orifice 42. The end of the tube 31 on the front of the board adjacent the clamp 19 is connected by suitable means 43 such, for example, as a properly reinforced rubber tube to the downstream side of the orifice 42. The tube 31 contains a liquid of proper specific gravity such, for example, as mercury, in order that the difference in pressure between the upstream and downstream sides of the orifice causes a change in level in the liquid in the tubes 31 and 31'. The change in level in the tube 31 causes the liquid to move back and forth across the board and is read with relation to the graduations 45 on the board below the tube 31.

In the ordinary boiler operation, variable loads are encountered due to the demand placed upon the prime movers to which the steam is delivered. This variation is beyond the control of the boiler attendant and in order to compensate for these variable loads he must change the speed of operation of the various devices which are within his control, in order that the relation between all the factors governing the operation of the boiler may be that which gives most efficient performance. The mechanisms which are most commonly controllable by a boiler room attendant are the speed of a stoker 48 and of a blower 49. In order that these factors may be graphically shown juxtaposed to the indication of the load shown in tube 31, I place an impeller pump 51 of well-known construction on the stoker drive mechanism. As is well-known, the pressure developed by an impeller pump is proportional to some function of speed of the pump. I therefore connect the circulating system of the

pump 51 by means of a tube 52 to the tube 31^a on the board 11. While any liquid may be used in the pump, I have found it advantageous to use a mineral oil such as is ordinarily used for lubrication; and, should it be so desired, this impeller pump might well be used to supply lubricating oil for the stoker drive mechanism. The speed of the stoker drive mechanism, which regulates the amount of fuel fed to the furnace per hour, produces a variation of pressure in the tube 52. The tube 52 is connected with the tube 31^a and variations of pressure in tube 52 cause the liquid in the tube 31^a to travel back and forth across the face of the board. In the case of the tube 31^a the end adjacent the clamp 19 is left open to the atmosphere. The tube 31^a is straight or curved as is found necessary from the curve A—A in Fig. 5. The relative curvature of the tubes 31 and 31^a and their inclination is such that for any given rate of evaporation of water shown in tube 31 the corresponding fuel delivery rate in pounds per hour is that vertically above. Thus, when the boiler room attendant observes a fluctuation in the liquid in the tube 31 he has only to regulate his stoker feed mechanism to bring the liquid in the tube 31^a vertically above that in tube 31.

In addition to controlling the amount of fuel delivered to the furnace 53 the boiler room attendant must also regulate the draft. This is done by regulating the speed of a blower 49 which delivers a current of air through the stoker wind box 54 to the furnace 53. In order that the speed of the blower 49 may be correlated to the load, I provide an opening 56 in the wind box 54 and connect the tube 31^d to the opening 56 through a tube having a vertical portion 57 adjacent the indicator board, the tube 57 and the tube 31^d which is open to the atmosphere at the end adjacent the clamp 19 forming a manometer for indicating the static head in the stoker wind box. The curvature and inclination of the tube 31^d relative to the tube 31 would be determined from the curve D—D in Fig. 5 and would be such that for any load the level of the liquid in the tube 31^d which indicates the correct static pressure would be vertically above the liquid in the tube 31 indicating that load. Thus, the boiler room attendant on noting a fluctuation in the load regulates the speed of the fan 49 to bring the level of the liquid in tube 31^d above that in 31. By the aid of this device the boiler room attendant is able to regulate the mechanism at his command in accordance with the fluctuation of the load imposed upon the boiler attendant upon various demands of the prime mover by simply noting whether the liquids in the various tubes are vertically one above the other.

In addition to the stoker speed and the pressure in the stoker wind box there are

two other phenomena which are important in maintaining efficient operation of the boiler. These are to a great degree dependent on the amount of fuel fed to the furnace and to the pressure of air under the grate but they require careful observation and I have accordingly provided for their indication on the instrument board. These are the drop in pressure through the passes of the boiler and the temperature of the gas at the exit from the boiler to the uptake. To indicate these I have provided a tube 31^b for indicating the pressure drop through the passes and a tube 31^c for indicating the temperature of the gases at exit. The tube 31^b is connected by means of connections 61 and 62 with the first pass 63 and the last pass 64, respectively, of the boiler 66. The connection 61 includes a substantially vertical section adjacent the tube 31^b forming therewith a manometer indicating the difference in pressure in the front and rear passes of the boiler. The tube 31^c which is preferably sealed at the end adjacent the clamp 19 is connected with a pyrometric element 68 in the uptake 69. The pyrometric device 68 may comprise a vessel 70 containing some volatile liquid evaporable at ordinary flue gas temperatures thereby creating a pressure in the conduit leading to the tube 31^c. The pressure reading of the liquid in the tube 31^c is thus indicative of the temperature in the uptake 69. The curvature and inclination of the tubes 31^b and 31^c with respect to the tube 31 are derived from the curves B—B and C—C respectively of Fig. 5 and are such that when the boiler is operating under the most efficient conditions for any given load, as indicated in the tube 31, the surfaces of the liquids in tubes 31^b and 31^c are vertically above the surface of the liquid in tube 31.

It is thus apparent that I have devised an indicator in which the indications of most efficient operation bear simple relation one to the other, that is, they are arranged in a straight line. The most unskilled observer is thus enabled to note any discrepancy from the efficient setting without the use of tables or calculations of any manner whatsoever.

While I have shown my invention in but one form, it will be obvious to those skilled in the art that it is not so limited, but is susceptible of various other changes and modifications, without departing from the

spirit thereof, and I desire, therefore, that only such limitations shall be placed thereupon as are imposed by the prior art or as are specifically set forth in the appended claims.

What I claim is:

1. A correlating indicator comprising a board having a number of openings arranged in a straight line, tubes extending through said openings and bent into substantial parallelism with the board and adjustable clamping means for clamping said tubes adjacent their extremities opposite to said holes, said tubes being curved with respect to each other by an amount dependent upon the characteristic curves of the phenomena which they are designed to indicate.

2. The combination with a power-generating system subject to load fluctuations between predetermined minima and maxima and embodying various pieces of apparatus in each of which the activity varies in accordance with a predetermined law upon a load change, of means for developing a pressure at a central point proportional to the activity of each piece of apparatus, respectively, and a manometric tube for each of said pieces of apparatus at said central point subject to the pressure thereupon and shaped in accordance with the law governing the associated piece of apparatus, whereby the degrees of activity of the various pieces of apparatus are reduced to a common scale, the adjustment being such that the various indications bear a distinctive relationship upon the proper functioning of each piece of apparatus, at a given load, and not otherwise.

3. The combination with a stoker fired boiler furnace, of means for simultaneously registering on a single device the load on the boiler and pressures obtaining in various parts of the furnace in their proper relations to the load on the boiler, a rotary member of the stoker, a pump driven by the rotary member and developing a pressure which is a function of the speed of the stoker and consequently the fuel delivered thereby to the furnace, and means for registering the pressure developed by the pump in terms of rate of fuel fed to the furnace in its proper relation to the other data registered on the device.

In testimony whereof, I have hereunto subscribed my name this tenth day of November 1924.

HARRY H. BATES.
